(57) CLAIM

I claim, the ornamental design for a cutting board assembly, as shown and described.

DESCRIPTION

FIG. 1 is a partially exploded perspective view of a first embodiment of a cutting board assembly, showing my new design, comprising the components of a cutting board, a colander, a first larger container, and a smaller second container;

FIG. 2 is a perspective view of the first embodiment of the cutting board assembly in an assembled state;

FIG. 3 is a perspective view of the cutting board thereof;

FIG. 4 is a top plan view of the cutting board thereof;

FIG. 5 is a bottom plan view of the cutting board thereof;

FIG. 6 is a front elevational view of the cutting board thereof;

FIG. 7 is a right side elevational view of the cutting board thereof, the left side elevational view being substantially similar;

FIG. 8 is a perspective view of the colander thereof;

FIG. 9 is a top plan view of the colander thereof;

FIG. 10 is a bottom plan view of the colander thereof;

FIG. 11 is a front elevational view of the colander thereof;

FIG. 12 is a right side elevational view of the colander thereof, the left side elevational view being substantially similar;

FIG. 13 is a perspective view of the larger first container thereof;

FIG. 14 is a top plan view of the larger first container thereof;

FIG. 15 is a bottom plan view of the larger first container thereof;

FIG. 16 is a front elevational view of the larger first container thereof, the rear side elevational view being substantially similar;

FIG. 17 is a right side elevational view of the larger first container thereof, the left side elevational view being substantially similar;

FIG. 18 is a perspective view of the smaller second container thereof in an erected state;

FIG. 19 is a top plan view of the smaller second container thereof;

FIG. 20 is a bottom plan view of the smaller second container thereof;

FIG. 21 is a front elevational view of the smaller second container thereof in an erected state, the rear elevational view being substantially similar;

FIG. 22 is a right side elevational view of the smaller second container thereof in an erected state, the left side elevational view being substantially similar;

FIG. 23 is a right side elevational view of the smaller second container thereof in a collapsed state, the left elevational view being substantially similar.

FIG. 24 is a partially exploded perspective view of a second embodiment of a cutting board assembly, showing my new design, comprising the components of a cutting board, a container, a larger first colander, and a smaller second colander;

FIG. 25 is a perspective view of the second embodiment of the cutting board assembly in an assembled state;

FIG. 26 is a perspective view of the cutting board thereof;

FIG. 27 is a top plan view of the cutting board thereof;

FIG. 28 is a bottom plan view of the cutting board thereof;

FIG. 29 is a front elevational view of the cutting board thereof, the rear side elevational view being substantially similar;

FIG. 30 is a right side elevational view of the cutting board thereof, the left side elevational view being substantially similar;

FIG. 31 is a perspective view of the container thereof;

FIG. 32 is a top plan view of the container thereof;

FIG. 33 is a bottom plan view of the container thereof;

FIG. 34 is a front elevational view of the container thereof, the rear elevational view being substantial similar;

FIG. 35 is a right side elevational view of the container thereof, the left side elevational view being substantially similar;

FIG. 36 is a perspective view of the larger first colander thereof;

FIG. 37 is a top plan view of the larger first colander thereof;

FIG. 38 is a bottom plan view of the larger first colander thereof;

FIG. 39 is a front elevational view of the larger first colander thereof;

FIG. 40 is a right side elevational view of the larger first colander thereof, the left side elevational view being substantially similar;

FIG. 41 is a perspective view of the smaller second colander thereof in an erected state;

FIG. 42 is a top plan view of the smaller second colander thereof;

FIG. 43 is a bottom plan view of the smaller second colander thereof;

FIG. 44 is a front elevational view of the smaller second colander thereof in an erected state, the rear elevational view being substantially similar;

FIG. 45 is a right side elevational view of the smaller second colander thereof in an erected state, the left side elevational view being substantially similar; and,

FIG. 46 is a right side elevational view of the smaller second colander thereof in a collapsed state, the left side elevational view being substantially similar.
